(57) **CLAIM**

The ornamental design for a portable electric driver drill, as shown and described.

DESCRIPTION

FIG. 1 is a front elevational view of the portable electric driver drill;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a top and left front perspective view thereof;

FIG. 8 is a top and right front perspective view thereof; and,

FIG. 9 is a top and right rear perspective view thereof showing a body portion thereof in which a drill bit is detachably attached, a hook being shown to be attached to a rear side of the portable electric driver drill, while the hook can also be attached to a front side thereof as shown in FIGS.
